WHEEL FLANGE OILER

Sidney E. Bates and Emmons Overmier, Chicago,
Ill., assignors, by mesne assignments, to Poor &
Company, a corporation of Delaware

Application October 4, 1929, Serial No. 397,413

18 Claims. (Cl. 184—3)

This invention relates to certain new and useful improvements in wheel flange oilers, and more particularly to an improved device for distributing lubricant to the inner face of the rail head of 5 a rail and to the inner faces of the car wheel flanges in railroad equipment.

Numerous devices have heretofore been proposed for lubricating the engaging inner faces of wheel flanges and rails, particularly adjacent 10 curves where centrifugal force causes an enormous lateral thrust of the wheel flanges against the rail and the wear of these engaging parts is considerable unless they are properly lubricated. The apparatus herein disclosed involves 15 certain improvements on the type of wheel flange oiler disclosed in the copending applications of Sidney E. Bates, Serial No. 277,524 and 301,741, filed May 14, 1928 and August 24, 1928 respectively.

20 One object of the invention is to provide a means for distributing the oil from a single pumping mechanism equally at a plurality of longitudinally spaced points along the rail.

Another object is to provide an improved form 25 of car-wheel operated pumping mechanism.

Another object is to provide an improved form of oil distributing plate and wiper.

Other objects and advantages of this invention 30 will be more apparent from the following detailed description of one approved form of mechanism involving the principles of this invention.

In the accompanying drawings:

Fig. 1 is a plan view of the apparatus assembled 35 on the rail and adjacent thereto.

Fig. 2 is a transverse vertical section, taken substantially on the line 2—2 of Fig. 1, and on a larger scale.

Fig. 3 is an elevation of the distributing plates at the inner side of the rail.

40 Fig. 4 is an elevation of the pump operating mechanism at the outer side of the rail, certain of the parts being broken away and certain parts being shown in section to facilitate the disclosure.

Fig. 5 is a transverse vertical section, on a larger 45 scale, taken substantially on the line 5—5 of Fig. 3.

Fig. 6 is a view similar to Fig. 5 taken substantially on the line 6—6 of Fig. 3.

The oil supply mechanism comprises a metallic 50 casing 1, all except the upper portion of which may be embedded in the road-bed 2 adjacent the outer side of the track-way. The upper portion of this casing houses an oil reservoir 3 provided with a cover 4 hinged to the main casing at 5. Any suitable locking means may be provided at 55 6 to hold the cover in closed position. A follower

7 is fitted for vertical sliding movement within the cylindrical reservoir 3. As the oil is removed from the lower end of the reservoir, this follower 7 will be forced down by atmospheric pressure and will keep the upper surface of the thick oil or grease supply substantially level and prevent holes from being sucked therethrough. A central opening 8 in follower plate 7 is normally sealed by a plate 9, held down by a screw clamp 10. By loosening the screw device 10, the plate 9 may be 10 raised, thus permitting the follower 7 to be raised by the handle 11 of the screw device in order to replenish the supply of oil in the reservoir. A pump 12 of any suitable type, for example, a gear pump, is mounted in chamber 13 in the lower portion of casing 1 beneath the reservoir 3. The inlet 14 of pump 12 communicates with a pocket or hopper 15 leading from the bottom of reservoir 3. A screen 15a, provided with handles 15b by means of which it can be lifted out for cleaning 15 purposes, is positioned in the top of hopper 15. The outlet 16 of the pump leads into a conduit 17 which at one side of casing 1 leads to a horizontal outlet passage 18 having outlet openings at each end thereof. A sprocket chain 19 located in a 20 vertical chamber 20 at one side of casing 1 connects the sprocket wheel 21 on the rotary actuating shaft 22 of pump 12 with a sprocket 23 mounted on a driving shaft 24 journaled in the upper portion of casing 1 and projecting toward the 25 adjacent rail.

A filler plate 26 is positioned along the adjacent outer face of rail 25 between the head 27 and base flange 28 thereof, and a supporting plate 29 is secured along the outer face of filler plate 26. 30 The plates 26 and 29 may be secured to the rail in any suitable manner, as by means of the bolts 30 extending through the web 31 of the rail and the distributing means on the opposite side of the rail as hereinafter described. Supporting 35 plate 29 is formed along its lower edge with a plurality of outwardly extending brackets 32, 33, 34 and 35. One end 36 of an operating bar 37 is pivoted on a pin or shaft 38 mounted in plate 29 and a bracket arm 39 extending upwardly from 40 bracket 32. The other end 40 of operating bar 37 is provided with a perforated ear 41 guided for 45 vertical movement on a guide pin 42. This guide pin 42 is here shown in the form of a threaded bolt mounted at its lower end in bracket 35 and 50 provided with a nut 43 for limiting the upward movement of ear 41 on bar 37. The central portion of operating bar 37 is cammed upwardly at 43 so as to normally project above the upper surface of rail head 27 at one side thereof and lie in 55

the path of the tread of a car wheel as it passes along the rail. Compression springs 44 and 45 are confined between the stationary brackets 33 and 34 on plate 29 and brackets 46 and 47 on bar 5 37, these springs normally holding the bar 37 up in the path of the car wheel, this position of the bar being limited by the adjustment of nut 43 on the guide bolt 42.

A horizontal rotary shaft 48 is journaled in a 10 pair of spaced brackets 49 and 50 carried by supporting plate 29. Shaft 48 projects at right angles to rail 25 and in substantial alignment with the rotary shaft 24 of the pumping mechanism, being connected with this shaft through the universal joints 51 and 52 and the intermediate telescopic shaft section 53. This flexible shaft connection permits the mechanism to operate satisfactorily even though the casing 1 should not be mounted in exact alignment with the operating 15 mechanism on the rail. A ratchet wheel 54 and a pair of friction plates 55 are freely mounted on shaft 48 between a fixed plate 55' on the inner end of the shaft and the inner end of a bearing thimble 57 slidably keyed to the shaft and rotatable in bracket 50. A compression spring 56 confined on the outer end of shaft 48 between the 20 slide bearing 57 and an adjusting nut 58 on the shaft tends to push the bearing 57 inwardly and clamp the ratchet 54 between the friction plates 25 55 so that the ratchet wheel will normally rotate with the shaft. A pawl 59 is pivoted at its upper 30 end 60 to the operating bar 37 and is provided with a series of teeth 61 adapted to engage one side of ratchet wheel 54 and rotate this wheel in a clockwise direction, as seen in Fig. 4, when the 35 operating bar 37 is depressed. A spring pressed plug 62 mounted in stationary member 63 holds the pawl 59 yieldably in engagement with the ratchet wheel. A locking pawl 64 provided with 40 teeth adapted to engage the opposite side of the ratchet wheel is pivotally suspended at its upper end 65 in a stationary bracket 66, in which is mounted a spring pressed plug 67 similar to the device 62 for holding the locking pawl yieldably 45 against the ratchet wheel.

It will now be apparent that as a car wheel 50 passes along the track 25, it will engage the elevated portion 43 of operating bar 37 and depress the bar against the resistance of springs 44 and 45, thus pushing down the pawl 59 and imparting a 55 rotative movement to the ratchet wheel 54, which through the friction connections already described will rotate the shaft 48. Normally the shaft 48 and ratchet wheel 54 rotate as a unit, the only purpose of the frictional connection being to prevent breakage of the parts in case a stoppage occurs at any point in the chain of operating mechanism. After the car wheel has passed over the portion 43 of operating bar 37, this bar will 60 be elevated by the expansion of springs 44 and 45 to its original position, as shown in Fig. 4. The locking pawl 64 will prevent retrograde rotation 65 of the ratchet wheel 54 at this time, the spring device 62 yielding to permit the pawl 59 to slide upwardly at the opposite face of the ratchet wheel. As each car wheel passes over this operating mechanism, a series of successive partial rotations in the same direction will be imparted to shaft 48, this rotation being transmitted through the driving connections already described to the pump actuating shaft 22, thus causing the pump 70 12 to slowly force a stream of lubricant from reservoir 3 through the discharge conduit 17.

A shield 68 is secured to the side of operating bar 37 and projects over the pawl and ratchet 75

mechanism, so as to serve as a protective covering therefor. A larger stationary shield 69 is supported from plate 29 and projects outwardly over all of the operating mechanism mounted against the outer side of the rail. This shield is long enough to cover the inlets to the distributing plates, as hereinafter described. The shield 69 is centrally recessed at 70 to permit the operating bar 37 and shield 68 to move vertically there-through.

Inner and outer filler plates 71 and 72 are secured in any suitable manner to the opposite or inner face of the rail 25, as by the bolts 30 already referred to. These plates are adapted to fit the space between the head and base flange of the rail and are so proportioned that the outer face of filler plate 72 will lie in substantially the same vertical plane as the inner side face of the rail head 27. The oil-distributing plates are secured against the aligned outer faces of the filler plate 20 72 and rail head 27 by two rows of screw bolts 96 and 97 extending through the distributing plate into filler plate 72. In the present example, there are two of these plates 73 and 74 positioned end to end. Each of these plates is several feet in length 25 and the two plates are substantially identical so that a description of one will suffice for both.

The upper portion of plate 73 is beveled upwardly at 75 to a thin upper edge 76 so that this bevel surface will substantially fit the inner surface of a car-wheel flange and frictionally engage the same to serve as a wiping means for spreading the oil or other lubricant around the inner surface of the flange. The exposed end portion of beveled surface 75 is beveled off laterally, as 35 indicated at 77, where the wheel flange first engages therewith. The opposite end of the other distributing plate 74 will be similarly beveled at 78. A plurality of spaced oil pockets 79, 80, 81 and 82 are formed in the upper edge 76 of each 40 distributing plate. These pockets are arranged symmetrically in the plate and the pair of pockets 79, 80 are spaced the same distance apart as the pair 81, 82. The rear surface of the distributing plate is recessed at 83 to receive a thin metal 45 gasket plate 84 which extends longitudinally of the plate beyond the last pockets 79 and 82 formed therein. A main longitudinal oil channel 85 is formed in the bottom of recessed portion 83, this channel extending along the lower portion of plate 73 from a point midway between pockets 79 and 80 to a point midway between pockets 81 and 82. Branch conduits or channels 86 and 87 lead upwardly at similar angles, but in opposite directions from one end of main channel 85 to the 50 respective oil pockets 79 and 80. Similar branch channels 88 and 89 lead from the other end of the main channel to pockets 81 and 82. The branch channels 86, 87, 88 and 89 will all be of the same length. It will now be seen that the gasket plate 84 is clamped between the distributing plate 73 and filler plate 72 and serves as the rear wall of the several oil channels or conduits just described. At the mid portion of main channel 85 an inlet port 90 is formed in this channel and also through 55 the gasket plate 84 to communicate with a suitable inlet conduit 91 which extends through the web of the rail.

The inlet conduits 91 are connected at the opposite side of the rail through elbows 92 and flexible 70 conduits 93 with elbows 94 mounted in the opposite ends of the horizontal discharge conduit 18 of the oil supply mechanism.

It will now be seen that the entire-oil-distributing system is symmetrically designed from end 75

to end thereof, and that although a single pumping mechanism is used to supply oil to eight separate discharge pockets, the conduits leading to each pocket are of the same size and same length 5 as measured from the source, so that the resistance to the flow of lubricant to each pocket will be equal and the oil will be uniformly distributed among the several pockets. The cross-sectional area of each lubricant duct leading to a pocket 10 is much smaller than the pocket so that the body of lubricant in the pocket relieves the pressure on the lubricant at the discharge orifice of the pocket. It is not desirable that the oil or other heavy lubricant be projected outwardly from the 15 pockets with any force, but it should merely be caused to ooze up in these pockets so as to stand in the path of the car wheel flange and be smeared thereon and along the beveled wiping surface 15 so as to uniformly lubricate the entire wheel 20 flange and subsequently be carried by the wheel flanges onto the inner surface of the rail head along the adjacent curve. It will be noted that the successive impulses given to the pumping mechanism are quite small, and the single stream 25 of oil forced out by the pump is divided between a plurality of distributing pockets so that the oil will not be ejected from these pockets by the sudden sharp impulses given to the operating bar 37 by the successive car wheels as they pass along 30 the track.

A trough 95 may be secured in any suitable manner, as by means of the screw bolts 96, to the outer face of each distributing plate, so as to catch any excess oil that flows from the distributing pockets and is not carried away by the wheel flanges. These troughs can be emptied at suitable intervals by the track crew, and thus tend to keep the adjacent portions of the road-bed in cleaner condition.

40 It will be noted that while the operating and distributing mechanisms are firmly mounted against opposite sides of the rail, these parts are connected through the flexible shaft 53 and flexible oil conduits 93 with the oil reservoir and pumping mechanism, which are independently mounted in the adjacent road-bed. This will permit the rail and parts carried thereby to weave vertically as a train passes thereover, and also does not necessitate an exact alignment of the 45 reservoir and pumping mechanism with the rail-carried parts.

It is to be understood that this apparatus is particularly adapted for distributing a thick oil or other heavy lubricant, as best adapted for the 55 greasing or lubrication of the engaging surfaces of car wheels and rails. Wherever the term "oil" is used in the above specifications or in the claims which follow, it is intended to cover all such heavy lubricants.

60 We claim:

1. In a wheel flange oiler, a distributing plate adapted to be mounted adjacent the inner side of the rail and having a beveled upper edge portion adapted to engage the inner face of the wheel flange, lubricant distributing open pockets positioned at spaced intervals in the upper edge of the plate, means for feeding lubricant into the plate, lubricant distributing passages in the form of grooves arranged in the back face of the plate and leading to the pockets, and means on the back face of said plate for closing the open sides of said grooves.

2. In a wheel flange oiler, a filter plate adapted to be anchored to a rail between the head and base flange thereof with its outer vertical face ex-

tending substantially in the same plane as the adjacent outer face of the railhead, and a renewable oil-distributing plate having a beveled upper edge portion adapted to engage the inner face of a wheel flange, said plate being secured against the outer faces of the filter plate and railhead and having oil-distributing passages formed therein and terminating in the upper beveled edge portion of the plate at the side of the railhead. 5

3. In a wheel flange oiler, a filter plate adapted to be anchored to a rail between the head and base flange thereof with its outer vertical face extending substantially in the same plane as the adjacent outer face of the railhead, and a renewable oil-distributing plate having a beveled upper edge portion adapted to engage the inner face of a wheel flange, said plate being mounted on the filter plate with its rear face clamped against the outer faces of the filter plate and railhead and having oil-distributing passages formed in its rear 10 face and terminating in outlets formed in the upper beveled edge portion of the plate at the side of the railhead. 15

4. In a wheel flange oiler, a filter plate adapted to be anchored to a rail between the head and base flange thereof with its outer vertical face extending substantially in the same plane as the adjacent outer face of the railhead and a renewable oil-distributing plate adapted to be secured against the outer faces of the filter plate and railhead and having oil-distributing passages formed therein and terminating in the upper edge portion of the plate at the side of the railhead and a trough secured to the outer face of the distributing plate for catching surplus lubricant. 20 25 30

5. In a wheel flange oiler, a filter plate adapted to be anchored to a rail between the head and base flange thereof with its outer vertical face extending substantially in the same plane as the adjacent outer face of the railhead, a renewable oil-distributing plate adapted to be secured against the outer faces of the filter plate and railhead and having a beveled upper edge portion adapted to engage the inner face of a wheel flange, a gasket adapted to be clamped between the filter plate 40 and distributing plate, the inner face of the distributing plate being recessed to receive the gasket, there being a plurality of oil-distributing pockets formed in the upper beveled edge portion 45 of the distributing plate and a plurality of oil passages formed in the rear of this plate and leading to the pockets, the gasket forming the rear wall of the channels. 50

6. In a wheel flange oiler, a filter plate adapted to be anchored to a rail between the head and base flange thereof with its outer vertical face extending substantially in the same plane as the adjacent outer face of the railhead, a renewable oil-distributing plate adapted to be secured against the outer faces of the filter plate and railhead and having a beveled upper edge portion adapted to engage the inner face of a wheel flange, a gasket adapted to be clamped between the filter plate and distributing plate, the inner face of the distributing plate being recessed to receive the gasket, there being a plurality of oil-distributing pockets formed in the upper beveled edge portion 55 of the distributing plate, a longitudinal oil passage formed in the rear surface of the distributing plate, a plurality of branch passages leading 60 from the main passage to the several pockets, the gasket forming the rear wall of the several passages. 65

7. In a wheel flange oiler in combination with a reservoir, mechanism for pumping oil from the 70 75

- reservoir and means for delivering this oil to the wheel flange, means for operating the pumping mechanism comprising a rotary shaft, a ratchet wheel on the shaft, an operating bar mounted for vertical movement adjacent the railhead and having a cam portion projecting up into the path of a car wheel, spring means for normally elevating the bar, an operating pawl mounted on the bar and engaging the ratchet, a locking pawl mounted to engage the ratchet and prevent retrograde movement thereof when the operating bar is elevated, a shield mounted on the operating bar and covering the ratchet and pawl mechanism, and a stationary shield covering all of the operating mechanism and recessed to permit the cam portion of the bar and the shield thereon to move vertically therethrough.
5. In a wheel flange oiler in combination with a reservoir and pump mounted in the roadbed adjacent the outer side of a rail, a rotary shaft mounted adjacent the outer face of the rail, a flexible shaft connecting the rotary shaft with the pump, a pair of distributing plates each provided with a plurality of spaced oil outlets, the plates being positioned end to end at the inner side of the rail, oil conduits leading through the rail-web to the central portion of each distributing plate, flexible conduits leading from the pump to the inlet of each conduit, an operating bar positioned for vertical movement adjacent the outer face of the railhead and having a portion projecting up into the path of the tread of a wheel, a ratchet wheel on the rotary shaft, and a pawl carried by the operating bar and engaging the ratchet wheel, a shield carried by the operating bar and covering the pawl and ratchet mechanism, and a stationary shield covering the operating mechanism and the inlets to the conduits and recessed to permit the vertical movement of the central portion of the operating bar and the shield carried thereby.
10. In a wheel flange oiler in combination with a reservoir and pump mounted in the roadbed adjacent the outer side of a rail, a rotary shaft mounted adjacent the outer face of the railhead and having a cam portion projecting up into the path of a car wheel, spring means for normally elevating the bar, an operating pawl mounted on the bar and engaging the ratchet, a locking pawl mounted to engage the ratchet and prevent retrograde movement thereof when the operating bar is elevated, a shield mounted on the operating bar and covering the ratchet and pawl mechanism, and a stationary shield covering all of the operating mechanism and recessed to permit the cam portion of the bar and the shield thereon to move vertically therethrough.

8. In a wheel flange oiler in combination with a reservoir and pump mounted in the roadbed adjacent the outer side of a rail, a rotary shaft mounted adjacent the outer face of the rail, a flexible shaft connecting the rotary shaft with the pump, a pair of distributing plates each provided with a plurality of spaced oil outlets, the plates being positioned end to end at the inner side of the rail, oil conduits leading through the rail-web to the central portion of each distributing plate, flexible conduits leading from the pump to the inlet of each conduit, an operating bar positioned for vertical movement adjacent the outer face of the railhead and having a portion projecting up into the path of the tread of a wheel, a ratchet wheel on the rotary shaft, and a pawl carried by the operating bar and engaging the ratchet wheel, a shield carried by the operating bar and covering the pawl and ratchet mechanism, and a stationary shield covering the operating mechanism and the inlets to the conduits and recessed to permit the vertical movement of the central portion of the operating bar and the shield carried thereby.
15. In a wheel flange oiler in combination with a reservoir and pump mounted in the roadbed adjacent the outer side of a rail, a rotary shaft mounted adjacent the outer face of the railhead and having a cam portion projecting up into the path of a car wheel, spring means for normally elevating the bar, an operating pawl mounted on the bar and engaging the ratchet, a locking pawl mounted to engage the ratchet and prevent retrograde movement thereof when the operating bar is elevated, a shield mounted on the operating bar and covering the ratchet and pawl mechanism, and a stationary shield covering all of the operating mechanism and recessed to permit the cam portion of the bar and the shield thereon to move vertically therethrough.

9. A lubricating device comprising an operating member adapted to be disposed adjacent a track rail and adapted to be operated upon the passage of a car over the track, a lubricant reservoir supported in a fixed position in the road-bed and adapted to be disposed at a position remote from the track and independent of the movement thereof, a conduit for delivering lubricant from the reservoir to a point adjacent the track, pump means disposed substantially at the location of the reservoir to effect the delivery of lubricant through the conduit, and flexible power transmitting means extending from the operating member to the pump means whereby the former may be effective for operating the latter.

10. In a wheel flange oiler, a filler plate adapted to be secured to the rail in the space between the head and the base flange of the rail with its outer face forming a continuation of the adjacent vertical face of the rail head, and a renewable oil-distributing plate provided on its inner face with oil distributing grooves terminating in discharge openings in the upper edge portion of the plate and adapted to be clamped against the outer face of said filler plate and said rail head to close the open sides of said grooves.

11. In a wheel flange oiler, a filler plate adapted to be anchored to a rail between the head and base flange thereof with its outer vertical face extending substantially in the same plane as the adjacent outer face of the railhead, and a renewable oil-distributing plate having a beveled upper edge portion, said plate being secured against the outer faces of the filler plate and railhead and

having oil-distributing passages formed therein and terminating in the upper beveled edge portion of the plate at the side of the railhead.

12. In a track oiling system, an oil supply means comprising a casing adapted to be partially embedded in the ballast at a location spaced from the rails and ties, a reservoir in the casing, a pumping mechanism in the casing adapted to withdraw lubricant from the reservoir and discharge it from the casing, and means operable by a car wheel comprising flexible shaft and conduit connections extending from a rail for operating the pumping mechanism and for delivering the lubricant to the rail.

13. In a wheel flange oiler, a lubricant distributing member comprising a plate adapted to be positioned longitudinally of a rail at the inner side thereof and having a beveled upper edge portion shaped to engage the inner surface of a wheel flange and serve as a wiping means, there being a lubricant channel extending longitudinally of the plate and a series of distributing channels leading at intervals from the lubricant channel to the upper edge portion of the beveled surface, and a flange member mounted at the front of the plate to form therewith a trough for catching excess lubricant.

14. In a wheel flange lubricator, a lubricant distributing plate adapted to be mounted on a rail to extend between the wheel flange and the head of the rail and having a pair of lubricant outlets in its upper edge portion and formed on a side face with a plurality of connected grooves which provide a main lubricant passage extending longitudinally of the plate to a point midway between said outlets and branch passages of equal length and cross sectional area leading from the main passage to the outlets, and means for closing the open sides of said grooves.

15. In a wheel flange lubricator, a lubricant distributing plate adapted to be mounted on a rail to extend between a wheel flange and the head of the rail and having a plurality of outlets in its upper edge and formed on its rear face with a plurality of connected grooves providing a main lubricant supply duct and pairs of branch ducts leading from the supply duct to said outlet, there being a centrally located inlet for the main duct and each pair of branch ducts being of equal length and cross-sectional area and communicating with said supply ducts at points equi-distant from its inlet, whereby the resistance to flow of lubricant will be uniform in all of said branch ducts, and means for closing the open sides of said grooves.

16. A wheel flange lubricator comprising a unit having a fixed position in respect to the road bed and comprising a lubricant supply vessel and a pump; a unit fixed to a rail so as to be movable therewith having an element for operating said pump; and a flexible transmission connection between said operating element and the pump.

17. A wheel flange lubricator comprising a unit having a fixed position in respect to the road bed and comprising a lubricant supply vessel and a pump; a unit fixed to a rail so as to be movable therewith having an element for operating said pump; and a flexible and longitudinally extensible transmission connection between said operating element and the pump.

18. In a wheel flange lubricator, the combination of a unit having a fixed relation with respect to the road bed and comprising a lubricant supply vessel and a pump; a unit fixed to a rail

and movable therewith comprising a lubricant distributing plate arranged adjacent the rail head and a pump operating element arranged adjacent the rail head and adapted to be depressed by the wheels of passing cars; a flexible driving connection for transmitting the move-

ment of said operating element to the pump; and a conduit having a flexible portion extending from the pump to said distributing plate.
